UNITED STATES PATENT OFFICE.

HENRY HESS, OF PHILADELPHIA, PENNSYLVANIA.

GAGE.

1,170,255.

Specification of Letters Patent.

Patented Feb. 1, 1916.

Application filed October 19, 1912. Serial No. 726,637.

To all whom it may concern:

Be it known that I, HENRY HESS, a citizen of the United States, residing at Philadelphia, in the county of Philadelphia and State of Pennsylvania, have invented certain new and useful Improvements in Gages, of which the following is a specification, reference being had therein to the accompanying drawing.

10 My invention relates to gages and more particularly to what may be termed fixed dimension gages, wherein in practical use there is no adjustment, the gaging surfaces being permanently set for a fixed size or dimension to which the object must accord. Certain features herein, however, are adaptable to other species of gages.

15 It is an object hereof to enable the advantageous employment in various types of gages such as end gages, length gages, etc., of preformed contact pieces, such for example as preformed hardened steel spheres which I prefer on account of the superior gage contacts and other advantages which 20 pertain thereto.

Another object hereof is to provide superior modes of attaching such preformed contact pieces to supports or handles.

Another object hereof is to provide superior modes of standardizing or correcting the size or dimension of a fixed dimension gage embodying a plurality of preformed contact pieces.

Other objects and advantages hereof will 35 appear in the hereinafter following description or will be apparent to those skilled in the art.

I will first describe one or more embodiments of my invention, and will thereafter 40 point out the novel features in the claims.

In the accompanying drawings forming a part hereof, Figure 1 is a side view partly in section of an end or length gage embodying the present invention. Fig. 2 is a top view of the gage seen in Fig. 1. Fig. 3 represents by itself a preformed contact piece such as may be employed in the present invention. Fig. 4 represents a spherical contact piece which has been machined away 45 to permit connection to support or handle in accordance with the present invention. Fig. 5 is an end view of the gage of Figs. 1 and 2. Fig. 6 is a perspective view showing the formation of the end of the support or handle before attachment to the contact piece or sphere, the position of the sphere 50 being shown in dotted lines. Fig. 7 represents in side view a modified form of gage embodying features of the present invention, the same shown partly in section to better disclose the interior construction. Fig. 8 is a top view of the end of the gage of Fig. 7. Fig. 9 represents partly in section the end of a still further modified gage embodying my invention. Fig. 10 represents the 55 contact sphere and a portion of the tubular support before attachment. Fig. 11 represents the first step in forming the attachment. Fig. 12 represents the final step in forming the attachment. Fig. 13 represents 60 in side view a completed end or length gage made in accordance with Figs. 9 to 12.

Similar letters of reference designate corresponding parts in the several figures of the drawings.

Referring first to the modification of Figs. 1 to 6, the gage therein shown comprises a preformed contact piece A and a supporting piece or handle B. For the reasons already stated, the contact piece is substantially of spherical form and may be constructed of a preformed hardened steel sphere A, Fig. 3. There will be at least one of these preformed contacts, and in the preferred embodiment shown there is one at 65 each end of the gage, so that the latter may be employed as an end or length gage with such contact pieces affording all the gaging contacts. According to this invention the connection between the contact piece A and the support B is made by forming the latter to grip the former, that is to say by bending portions of the support B around so as to grip the contact piece or sphere A. This I prefer to accomplish by forming recesses 70 75 80 85 90 95 100 105 110 115 120 125 130 135 140 145 150 155 160 165 170 175 180 185 190 195 200 205 210 215 220 225 230 235 240 245 250 255 260 those strips will engage the grooves *a* and may be by appropriate machinery tightly bent and pressed around and snugly into the grooves as seen in Figs. 1, 2 and 5, so as to form a permanent non-adjustable connection. Both ends of the gage being the same, we have the end or length gage shown in Figs. 1 and 2. Since, in constructing such gage, its length may not be accurate and may require to be standardized, I have devised an expedient for standardization. Thus as seen at C the tubular support B has spun or rolled circumferentially around it a shallow groove. Also it may have, if desired, an annular excrescence D spun from the interior before completion of the gage. If now the gage be found to be of slightly too great length, the spinning of groove C will shorten the instrument and thus permit standardization. An increase in the depth of groove C will decrease the length of the gage. If the gage be shortened too much or be originally constructed too short, the annular portion D may be rolled to flatten it somewhat, thus lengthening the gage. In this way we have complete ability to standardize.

Referring now to the modification of Figs. 7 and 8, the attachment or gripping of the sphere E by the support or handle F is different. In this case the support F has a single pair of projecting strips *f* of substantial width but of insufficient length to meet each other, so that when pressed into the sphere recesses *e* the sphere at the end of the gage will be maintained intact as before. For standardizing this instrument, I have shown the support F to be composed of separate members relatively adjustable as by screw threads. There may, for example, be three members, member *g* gripped to one sphere, member *g'* to the second sphere, and member G having screw engagement with both member *g* and *g'*. Obviously standardization is effected by relatively turning one or both of the members *g*, *g'* or the member G. When properly standardized soft solder may be applied to render the adjustment permanent, for example as shown at *g²* or *g³*.

Referring to the modifications of Figs. 9 to 13, this illustrates a mode of connection between contact piece and support or handle which obviates the machining of recesses in the contact piece or sphere. The result is shown in Fig. 9 wherein the sphere H is gripped around its entire circumference by the extreme or end portion *j* of the support or handle J. This construction may be produced in the following manner. Beginning with the sphere H and tubular support J as shown in Fig. 10, the metal of the latter may be swaged to an enlarged diameter, for example by forcing the sphere H into the tube, the latter being if desired supported against improper deformation by suitable dies. Fig.

11 shows the result of this step. Finally the enlarged or extreme portion *j* of the support J may be bent inwardly around the sphere H by spinning or otherwise, so as to produce the result shown in Fig. 12. If the gage is made in this manner at both ends the resultant will be as shown in Fig. 13, which also shows a spun groove C and a spun annular excrescence D as in Figs. 1 and 2 for standardizing the instrument.

It will be seen that by the foregoing described embodiments, I have attained the objects and advantages hereinbefore recited and referred to.

Since many features hereof may be employed without other features and may be variously modified in detail and form, I do not wish to be limited to matters of detail or form excepting as set forth in the appended claims.

What I claim and desire to secure by Letters Patent is:

1. In a fixed-dimension gage the combination of a spherical contact piece, and a support therefor, said support having a body part and gripping portions all constituted of a single integral piece of bent metal, and said gripping portions being bent permanently into place around the sphere so as to grip it rigidly by contact outside of its equator.

2. In a fixed-dimension gage the combination of a spherical contact piece, and a support therefor, said support having a body part and a plurality of gripping fingers each constituted of a single piece of bent metal, integral with said body portion and said fingers being bent permanently into place around the sphere so as to grip it rigidly outside of its equator.

3. In a fixed-dimension gage the combination of a spherical contact piece having finger receiving grooves, and a support therefor, said support having a body part and a plurality of gripping fingers all constituted of a single piece of bent metal, integral with said body portion and said fingers being bent permanently into place around the sphere so as to grip it rigidly outside of its equator in said grooves; the parts constructed and arranged to afford contact exposure of the sphere at the end and also at the sides of the gage.

4. In a fixed-dimension gage the combination of a spherical contact piece, and a support therefor, said support having a body part and a plurality of extensions, said extensions being bent permanently into place around the sphere so as to grip it rigidly outside of its equator, and the parts so constructed and arranged as to afford contact exposure of the sphere at the end of the gage and also at the sides thereof.

5. In a fixed dimension end or length gage the combination of a contact piece and a

tubular support having gripping extensions bent around said contact piece for permanently and immovably holding it, and means for standardizing the length of said gage by deformation of the support.

6. A fixed dimension end or length gage comprising a tubular portion having suitable contacts at its ends, and means for standardizing the length of the same comprising a spun portion capable of deformation.

7. A fixed dimension end or length gage comprising a tubular portion having suitable contacts at its ends, the same standardized as to its length by a groove or depression spun therein.

8. A fixed dimension end or length gage comprising a tubular portion having suit-

able contacts at its ends, the same capable of standardization as to its length by reason of an outwardly spun excrescence adapted to be depressed for lengthening.

9. A fixed dimension end or length gage comprising a tubular portion having suitable contacts at its ends, the same capable of standardization as to its length by a groove spun therein and by reason of an outwardly spun excrescence adapted to be depressed for lengthening.

In testimony whereof I affix my signature in presence of two witnesses.

HENRY HESS.
